UNITED STATES PATENT OFFICE.

THEOPHIL PFISTER, OF CHICAGO, ILLINOIS.

ORNAMENTING GLASS.

SPECIFICATION forming part of Letters Patent No. 625,464, dated May 23, 1899.

Application filed June 1, 1898. Serial No. 682,285. (No model.)

To all whom it may concern:

Be it known that I, THEOPHIL PFISTER, a citizen of the United States, residing at Chicago, in the county of Cook and State of Illinois, have invented an Improvement in Ornamenting Glass, of which the following is a specification.

Hollow articles, such as letters, usually of metal, have been caused to adhere to the surface of glass, and solid letters and other articles of an ornamental character have been applied both to the outer and the inner surfaces of windows or plates of glass.

The present invention relates to the ornamental character that is given to the hollow article that is affixed to the surface of the window or plate of glass. In my present invention the article to be affixed to the glass is made hollow and the hollow or concave side is filled with pieces of broken glass or prisms or pieces of ornamental materials, either plain, silvered, gilded, or colored, and an adhesive material is employed for holding the pieces together within the hollow letter or ornament and for causing such hollow letter or ornament to adhere to the surface of the glass.

By this improvement ornamental or artistic letters in great variety can be produced or the glass ornamented by vines, scrolls, leaves, or other designs, and the ornamental effects and the colors employed are largely under the control of the artist, so that the desired effects can be produced and in great varieties from similar or standard hollow letters or ornaments that are filled in.

In the drawings I have represented in Figure 1 a portion of a plate of glass with ornaments applied thereon, and in Fig. 2 a section of the same in a magnified size.

The plate of glass is illustrated at A, and a hollow letter is indicated at B. At C a hollow leaf and stem are illustrated and at D a hollow circular article similar to a watch glass or crystal, and it will be understood that the shapes employed are numerous and under the control of the artist.

In all instances the edges of the hollow article are to coincide with the surface of the glass to which they are to be attached. In other words, such edges are to be in a plane where the glass is flat, or they are to be curved when the plate of glass is a section of a cyl-

inder or other form, and I do not limit myself as to the manner in which the hollow articles are to be produced, as they will usually be of glass and may be molded, blown, pressed, or otherwise formed in any well-known manner.

Under all circumstances the hollow or concave portion of the article is filled with ornamental material of the desired color or character—such, for example, as pieces of broken colored glass, ornamental pieces of mineral substances, or pieces of material gilded or silvered—or foil or leaf metal may be introduced on the inner surface of the letter or other article previous to the filling material being introduced or in between the layers of filling material, and an adhesive material—such as liquid gelatin glue, silicate of soda or varnish, or any mixture of such substances—is to be filled into the conical article to cause the particles or pieces to adhere to the same and then to cause the article to adhere to the glass, plate, or other surface to which the article is to be affixed, and care should be taken to allow the cementing materials to dry, set, or harden sufficiently before the article is attached to the surface. It will usually be advantageous to allow such cementing materials to harden or set and then apply an adhesive material to the surface to cause the same to adhere to the plate of glass or other surface. Otherwise there would not be sufficient opportunity for the drying or setting of the adhesive materials made use of to cause the particles to adhere to each other and within the letter or other article.

While this improvement is especially available with translucent or transparent letters or other devices attached to the surface of the window or plate of glass, the improvement is available where the letter or ornament is transparent and concave for receiving the ornamental materials to be seen through the transparent letter or other article, and in this case such ornaments may be applied to a wall or other opaque backing.

I claim as my invention—

1. As a new article of manufacture, a letter or ornamental article hollow on the face side and with edges adapted to coincide with the plate of glass to which it is to be attached and such article filled in level with the edges with ornamental pieces of glass or similar

material and caused to adhere together and to the hollow article by an attaching cement or varnish, substantially as set forth.

2. As a new article of manufacture, a hollow letter or ornament of transparent material filled in with pieces of glass or other ornamental material and adhesive material for holding such ornamental pieces in position, the edges of the letter or ornament being

adapted to coincide with a plate of glass or other surface to which the letter or ornament is to be attached, substantially as set forth.

Signed by me this 27th day of May, 1898.

THEOPHIL PFISTER.
